United States Patent Office.

CHARLES A. COLE, OF ST. LOUIS, MICHIGAN, ASSIGNOR TO HIMSELF AND JOHN L. EVANS.

Letters Patent No. 95,195, dated September 28, 1869.

IMPROVEMENT IN VISSES.

The Schedule referred to in these Letters Patent and making part of the same.

To whom it may concern:

Be it known that I, CHARLES A. COLE, of St. Louis, in the county of Gratiot, and State of Michigan, have invented a new and useful Improvement in Adjustable Vises; and I do declare that the following is a true and accurate description thereof, reference being had to the accompanying drawings, and to the letters of reference marked thereon, and being a part of this specification.

Figure 1 is a perspective view of my invention.

Figure 2 is an elevation of the inner side of the front leaf.

Like letters indicate like parts in each figure.

The nature of this invention relates to an improvement in vises, namely, in the simplification of construction and arrangement of the several parts, by virtue of which I obtain a very efficient adjustable-jawed vise, at a cost less than that for which others operating on the same general principles can be obtained.

In the drawings—

A represents a leaf, the upper end of which terminates in a stationary jaw, *a*, and is provided with a lug, *b*, by means of which the whole is secured to a bench or table.

B is another leaf, hinged to the leaf A, at their lower ends, in the usual manner.

The spring C compels the upper ends of the parts of the vise to open when allowed to do so by the operation of the screw D.

The upper portion of the leaf B is enlarged, and squared at top, and its inner side, which is semi-circular in form, is provided with a channel, *c*.

E is a jaw, made substantially in the form shown in the drawings, and pivoted to the squared top of the leaf B, by means of the stud-screw *d* or a rivet.

This jaw is provided with a lug, *e*, and lip *f*, which engages with the channel *c* in the inner side of the leaf.

The jaw E being loosely pivoted, as described, will readily adapt itself to any angle with reference to the stationary jaw, or will stand parallel with the same if desired.

The lip *f*, engaging in the channel *c*, holds the jaw E in place, in connection with the stud-screw *d*.

What I claim as my invention, and desire to secure by Letters Patent, is—

The improved construction and arrangement of the several parts of the vise, as herein shown and described.

CHARLES A. COLE.
